A STENCIL FILLER SOLUTION

Earl G. Conley, Tulsa, Okla.

No Drawing. Application December 18, 1952,
Serial No. 326,668

4 Claims. (Cl. 106—171)

This invention relates to the art of stencil printing and surface ornamentation, and more particularly to the method and materials for preparing silk screens for use in printing designs by forcing inks, dye pastes and the like therethrough.

Sheets of waxed paper or films of cellophane, lacquers and the like for preparing stencils for silk screen printing have been in commercial use for some time, and in accordance with existing practices portions corresponding to the design to be printed are removed from the sheet by the use of a suitable solvent or by manually cutting the design therefrom and the remaining sheet then caused to adhere to the screen by the use of a hot iron or by means of a suitable solvent which renders the sheet tacky and capable of being adhesively secured to the screen.

In modern practice a film impervious to inks and the like to be used in the printing is mounted on a carrier and the design cut from the film. Once the film is cut the exposed surface thereof is placed in contact with fine silk fabric or other suitable material and a solvent applied to the surface of the film through the fabric, the solvent rendering the surface of the film tacky or adhesive and causing the entire film to adhere to the silk screen. The stencil film is usually mounted on the carrier sheet with a release compound or adhesive so that when the stencil film is adhered to the silk screen the carrier sheet is peeled away from the adhered stencil film. The fine silk fabric is, of course, mounted upon a suitable frame under sufficient tension to maintain the fabric smooth. In using such stencils the object to be printed is placed under the silk screen and inks or the like arranged in a reservoir area at one end of the frame are pulled across the film with a squeegee, forcing the ink through the cutout portions of the film and through the silk screen onto the object to apply the design thereto. In many instances the film does not cover the entire silk screen, or there may be a portion of the design which is not desired to be reproduced. In such instances it is common practice to use a stencil filler made from a lacquer base or the like and apply same with a brush to the areas of the silk screen which are desired to be ink impervious. Lacquer and acetate type fillers require expensive, explosively inflammable solvents and clean up thinners. Water-soluble stencil fillers have been used but such fillers use water in their formulation causing relatively slow drying. They also exhibit extreme expansion and contraction under conditions of excessive humidity.

The objects of the present invention are to provide a solvent adhering type, knife-cut stencil which is water-soluble and may be removed from the silk mesh after use by noninflammable materials such as water; to provide a solvent adhering type knife-cut stencil composed principally of water-soluble cellulose ether such as methylcellulose and a suitable plasticizer and coloring pigment, the film being mounted on a transparent backing sheet with a release compound whereby the backing sheet is removable from the film after the film is cut and adhered

2

to a silk screen mesh; to provide a silk stencil filler of water-soluble cellulose ether and volatile organic solvents which can be spread over the surface of silk screen stencils and quickly dried to form a cellulose film; to provide such a stencil filler that although originally deposited from an organic solvent may be easily removed with water; to provide such a stencil filler of principally methylcellulose and volatile organic solvents wherein the filler is fast-drying, the solvents are not explosively inflammable and when applied and dried the cellulose film is impervious to solvent action of all organic paint diluents and cleaners commonly used in the silk screen industry but is soluble in water eliminating the use of expensive, explosively inflammable solvents and clean up thinners.

In accordance with the present invention the stencil film is composed of a cellulose ether which is water-soluble, for example methyl-cellulose, and a plasticizer, such as sulfonated castor oil or triethanolamine, and suitable pigmentation may be added to the mixture of cellulose ether and plasticizer to provide desired color in the final film to aid in the detection of pinholes. The following examples of the film composition:

	Example I	Parts
Methyl-cellulose	80	
Sulfonated castor oil	20	

	Example II	Parts
Methyl-cellulose	80	
Triethanolamine	20	

The compositions, Examples I or II, or methyl-cellulose alone, are dissolved in water or a suitable organic solvent such as formamide, tetrachloroethane, bromoform, benzyl alcohol, ethylene chlorohydrin, ethyl glycolate, methyl salicylate, aniline, pyridine, quinoline or chloraniline. The solution may be applied by means of a coating machine, spraying or any other desired method to a carrier sheet to form a film. Two or more coats of the solution may be used to obtain a relatively thicker film. The film is then suitably dried by passing it through a drying oven or otherwise.

The carrier sheet is preferably cellophane, glassine paper or other transparent material which, before coating with the cellulose ether solution, had previously been coated with a release compound in the form of a rubber cement or other suitable material that will hold the cellulose ether film to the carrier sheet whereby the carrier sheet will serve as a backing sheet and permit the sheet to be peeled from the film after the film is adhered to a silk screen. The cellulose ether film also may be suitably formed and then such film applied to a backing sheet coated with a suitable release compound or adhesive to hold the film on said backing sheet during cutting and application to a silk screen. The film and transparent backing sheet are relatively transparent when placed in contact with art work or other designs which the operator may wish to reproduce. The patterns, letters or designs are cut through the cellulose film to the backing sheet by means of a sharp blade. Areas which are to be printed on the final stencil are lifted away from the backing sheet and discarded. When the design has been cut on the film a silk fabric which is stretched on a stencil frame is placed in close contact with the film and an adhering solution applied to the silk fabric by means of a solvent dampened cloth, the solvent penetrating the silk fabric causing the surface of the film contacting the silk fabric to become tacky and due to the pressure holding the film in contact with the silk fabric the film is adhered to the fabric when the adhering solution has dried.

The stencil frame is then lifted and the transparent backing paper is peeled away from the adhered stencil.

In further preparing the silk screen for use, the silk fabric around the margins of the stencil film or between the stencil film and the silk screen frame are rendered impervious to ink, dye paste and the like by means of a stencil filler consisting of a water-soluble cellulose ether, a volatile organic solvent or solvents and a plasticizer. A suitable pigmentation may be added to the mixture to give color to the filler film if desired. The water-soluble cellulose ether is preferably methyl-cellulose. The organic solvents may be selected from formamide, tetrachloroethane, bromoform, benzyl alcohol, ethylene chlorohydrin, ethyl glycolate, methyl salicylate, aniline, pyridine, quinoline, chloraniline, or a mixture of methyl-15 ene chloride, ethylene dichloride and carbon tetrachloride. Methylene chloride, ethylene dichloride and carbon tetrachloride are not individually solvents of methyl-cellulose but are cosolvents when used in combination with methyl alcohol. There are other organic solvents of 20 methyl-cellulose which could be used; however, it is preferable to utilize the most volatile solvents to obtain maximum rapidity of drying. Any suitable plasticizer for methyl-cellulose may be used; however, best results have been obtained by use of either sulfonated castor oil or triethanolamine. An example of a suitable mixture of the materials to form stencil filler is eight (8) ounces of methyl-cellulose, one (1) gallon of solvent and two (2) ounces of plasticizer and pigment if desired for coloring 25 the same.

In the above examples, specific proportions are mentioned but while these proportions are very suitable, I do not restrict the present invention to these proportions. The stencil filler solution when applied by a squeegee or brush onto the open silk mesh dries in three to five minutes in a tough, continuous film which fills the open mesh of the silk, thus producing a surface which is impervious to the action of paints, dye pastes and inks commonly used in silk screen process printing and their solvents. 30 This film exhibits very slight change in dimensional stability upon exposure to varying conditions of humidity. The stencil filler solution may also be used to spray or otherwise coat a backing sheet to form a knife-cut solvent adhering stencil film. The film when dry, although originally deposited from an organic solvent, may be easily removed with tap water. Also the non-inflammable solvent or water may be used for clean up on the stencil and after use of the stencil the stencil and the filler may be removed with ordinary tap water.

It is believed obvious that I have provided a solvent adhering, water-soluble, knife-cut stencil film and water-soluble stencil filler which reduce necessary time of preparing silk screens for use and also reduce the hazards connected therewith, as well as simplifying the removal of the stencil and filler from the silk screen.

What I claim and desire to secure by Letters Patent is:

1. A stencil filler solution consisting of methyl-cellu-

lose, a solvent consisting of a mixture of methylene chloride, ethylene dichloride, carbon tetrachloride and methyl alcohol, and triethanolamine, said solution being characterized by its being not explosively inflammable and its rapid drying when applied to a foraminous painting screen to form a film which is water soluble and is impervious to the solvent action of organic diluents and cleaners used in silk screen processes.

2. A composition which is not explosively inflammable and which when spread on a surface quickly dries in a cellulose film coating that is water soluble and is substantially impervious to the solvent action of organic paint diluents and cleaners used in silk screen processes, consisting of methyl-cellulose, a solvent consisting of a mixture of methylene chloride, ethylene dichloride, carbon tetrachloride and methyl alcohol, and a plasticizer.

3. A composition which is not explosively inflammable and which when spread on a surface quickly dries in a cellulose film coating that is water soluble and is substantially impervious to the solvent action of organic paint diluents and cleaners used in silk screen processes, consisting of a mixture of 80 parts methyl-cellulose and 20 parts sulfonated castor oil, and a solvent consisting of a mixture of methylene chloride, ethylene dichloride, carbon tetrachloride and methyl alcohol.

4. A composition which is not explosively inflammable and which when spread on a surface quickly dries in a cellulose film coating that is water soluble and is substantially impervious to the solvent action of organic paint diluents and cleaners used in silk screen processes, consisting of a mixture of 80 parts methyl-cellulose and 20 parts triethanolamine, and a solvent consisting of a mixture of methylene chloride, ethylene dichloride, carbon tetrachloride and methyl alcohol.
